INVENTOR.
SIMON ABRAHAMS
BY *Charles H. Wilson*
ATTORNEY

UNITED STATES PATENT OFFICE.

SIMON ABRAHAMS, OF NEW YORK, N. Y.

FUEL-FEEDING DEVICE.

Application filed September 13, 1922. Serial No. 587,869.

To all whom it may concern:

Be it known that I, SIMON ABRAHAMS, a subject of the Republic of Poland, residing in New York, county and State of New York, have invented certain new and useful Improvements in a Fuel-Feeding Device, of which the following is a specification.

This invention relates to devices for supplying fuel to internal combustion engines, and has to do more specifically with a device by means of which the fuel is supplied in accordance with the load on the engine, this governing feature being automatically operated.

One of the objects of this invention is to provide a new and improved fuel supplying device for the purposes set forth, by means of which the fuel supply may be automatically controlled in accordance with the load upon the engine.

Another object of the invention is to provide a new and improved device for supplying fuel, which shall not only automatically govern the fuel supply in accordance with the engine load, but also provide means by which the fuel supply may be regulated, thereby controlling the speed of the engine.

Another object of the invention is to provide a new and improved device for supplying fuel to internal combustion engines, which shall be automatically operated to provide a positive feed, and be capable of regulation, whereby to control the engine speed.

Another object of the invention is to provide a device of the type described, which shall provide a positive feed for the fuel to the engine, together with means by which this supply may be automatically controlled in accordance with the engine load, and regulated in advance so as to govern the engine speed.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings which are

to be taken as a part of this specification, and in which I have shown a preferred form of embodiment of my invention:

Figure 1 is a view in elevation of the device with various parts in cross-section.

Figure 2 is a view in cross-section of the pumping mechanism taken on the line 2—2 of Figure 1.

Figure 2^a is a cross-sectional view of a detail of the pump mechanism, taken on the line 2^a—2^a of Figure 2.

Figure 3 is a view in side elevation of a detail of the device, as indicated by the line 3—3 of Figure 1.

Figure 4 is a view partly in cross-section of a detail of the governing mechanism.

Figure 5 is a plan view in detail of various parts as taken on the line 5—5 in Figure 1; and

Figure 6 is a view of the air inlet.

With reference now to the drawings wherein similar reference characters refer to similar parts throughout the several views thereof, the reference character 1 indicates a base plate mounted conveniently on the engine bed, or in any other suitable location. Formed integrally with this base plate is a pair of hollow cylinders 2, 2, providing the pumping chambers of a device by means of which fuel is supplied to the engine. As is illustrated more clearly in Figure 2, fuel which may be gasoline, kerosene, or other materials of that character, is supplied from a suitable tank, or other storage container, through a conduit 3, which is connected by means of a unit 4 and suitable packing 5 to one end of a bushing 6, the upper end of which is slightly enlarged. This bushing 6, it will be noted, is anchored in position in the casting 7, which forms part of the wall of the pump chamber, by means of a threaded bushing 8, which engages in threads in the casting 7. A bushing 9, similar to the bushing 6, is also held in position with the casting 7, by means of the threaded bushing 8, bushing 9 being provided with a seat 10 for a poppet valve at its upper end. The poppet valve, designated as 11, is provided with a head 12, beveled to make a close fit with the seat 10, and has also a stem 13 which projects downwardly and is guided by means of a hollow

guide 14, mounted in arms extending inwardly from the sides of the bushing 9. It will be noted that suitable packing 15 is provided between bushings 6 and 9.

5 It will be seen then that fuel may enter through the conduit 3, pass upwardly through bushing 6 into a slightly enlarged chamber 16 formed partly by the bushings 6 and 9, then when the valve 11 is opened, 10 the liquid may pass upwardly and into a hollow chamber 17, formed in the casting 7. From here the liquid passes downwardly into a well 18 formed so as to make a chamber for the pump, the lower end of this 15 chamber being normally closed by means of a plug 19, provided with a well 20 formed in its upper face. Extending downwardly into the chamber 18 is a plunger 21, which passes through and is guided by suitable 20 gland nuts 22 and 23, which contain packing 24 compressed between them. These gland nuts are threaded into the wall of the casting formed in the body of the pump. At its upper end the plunger 21 will be seen 25 to be connected to a rack 25 extending vertically and guided in the walls of the casting 2.

On reference to Figure 2 it will be seen 30 that the pump structure is in duplicate, liquid being supplied by two conduits into similar chambers 18 mounted side by side on the base plate 1. The main body member, which will ordinarily be cast, has a plate 26 which extends above the chambers proper, 35 to provide guides for the racks 25. Mounted between the racks 25 on a stud 27 is a pinion 28 arranged so as to mesh with both racks. This stud will be seen to have a beveled end 29, the other end having a portion 30 of reduced diameter, and terminating in a threaded portion 31.

40 Mounted on the reduced shank 30 is a slotted cross-head 32, channeled along one face, as at 33. Keyed to the reduced shank 45 is a collar 34, having a projecting tongue 35 which rides in the channel 33. The cross-head is to be set with relation to the collar by means of a set screw 36, this set screw preventing downward movement of the 50 cross-head, the upward movement being prevented by friction produced by tightening the nut 37, mounted on the threaded portion 31 of the stud 27, suitable washers 38 underlying this nut. It will be seen by this 55 arrangement that by the tongue and channel construction of the cross-head and collar, together with the adjusting means provided, the cross-head may be set in various positions relative to the collar, but any rocking 60 movement of the cross-head will be in turn transmitted through the collar to the stud 27, and thence to the pinion 28. It will be seen further that the stud 27 projects a slight distance beyond the bearing block 39 65 in which it is mounted, thereby preventing

the collar 34 from being forced against the face of the bearing block as the nut 37 is tightened.

Pivotedly mounted in the lower end of the cross-head 32, by means of a bolt 40, to which 70 it is keyed by the key 41, is a link 42, which extends laterally for a considerable distance. At its other end, as is shown more clearly in Figure 3, the link 42 is pivotally mounted to a collar 43, mounted on a guide rod 44, 75 which runs between the free ends of a U-shaped member 45, the latter being mounted on a stud indicated in dotted lines at 46. This stud is carried in a bearing block 47, mounted on a base plate 48. At its rear end 80 there is fixed to the stud 46, an arm 49 provided at its end with a cam-follower 50, which rides on the face of a heart-shaped cam 51, mounted on a shaft 52, supported in a bearing 53 on the base 48. Fixed to 85 the shaft 52 is a spur gear 54, engaged by a pinion 55 mounted on a shaft 56, which is supported in base 48, shaft 56 being driven by the engine in any suitable manner. Also mounted on the shaft 52 is an eccentric link 57 to which is attached a pitman 58, operating a plunger 59, this plunger 90 acting as an air pump, and being used to supply pressure to the gas tank.

95 It will be noted that upon rotation of the shaft 55, which by the various connections causes the cam to rotate, the arm 49 will be caused to rock, in turn causing the U-shaped member 45 to rock, this causing 100 the link 42 to be given a reciprocatory motion. The motion of the link will be transmitted in turn to the cross-head, thereby causing the gear 28 to rock on its axis, this 105 rocking of the gear causing an up and down movement of the racks 25, which in turn is transmitted to the plunger 21. It will be noted that as one plunger is forced downwardly, the other is carried up.

110 Mounted in the casting which forms the body of the pump, directly above the inlet valve 11, is a bushing 60 provided with a seat 61, upon which rests a valve 62, having a stem 63 extending into a guide bushing 64, mounted in the casting, these bushings being held in place by a cap 65 held 115 in place in the main casting by screws 66. There is also provided a spring 67 encircling the guide bushing 64, and resting against the under side of the head of the valve, this spring having a container to force 120 the valve into position on its seat. At the upper end of the stem there is provided a regulating screw 68, which is threaded into the cap 65, a suitable gland 69 and packing 70 being provided so as to prevent leakage. This screw 68 will be seen to overlie the bore in the bushing 64, in which the stem 63 moves, so that by suitable adjustment the screw 68 may be regulated to prevent the valve 61 being forced too far from 125 130

its seat. Passageways 71, 71, are provided in the main casting on either side of the bushing 60, communicating with the interior of the bushing through suitable apertures. These passageways 71 in turn communicate with a conduit 72, through which the liquid is conducted to the interior of a bushing 73, in which is mounted a valve 74 held against its seat by means of a spring 75. It will be seen that the conduit 72 is held against the face of the bushing by means of a suitable cap-ring 76, together with packing 77. The bushing 74 is threaded into an angle T 78, having a branch 15 indicated by the line 79 through which branch the fuel passes to the engine manifold.

The T 79 is flanged at its other end, as at 80, the flange 80 abutting a similar flange 20 81 on a hollow casting 82. Mounted in the casting 82 is a bushing 83, through which the air is to be drawn into the engine, this bushing 83 being provided with a closure member 84, held in position by a spring 85 25 against the face of the bushing. This closure member is provided with suitable ports 86, by means of which the amount of air to be taken into the engine may be regulated.

Formed in the upper surface of the casing 30 82 is a plunger chamber 87, in which is mounted a plunger 88. This plunger is mounted on a stem 89, which projects in both directions beyond the plunger 88. Upwardly the stem passes through a cup-shaped disc 90 and at its upper end has a suitable nut and lock nut 91, 92, together with a disc 93. Encircling the upper end of the stem 89, is a coil spring 94, bearing against the disc 93 in one direction and 35 against the cup-shaped disc 90 in the other direction. Below the plunger 88 the stem 89 is provided with an integrally formed collar 95, upon which the plunger 88 rests, the stem 89 continuing downwardly 40 and entering a suitable guideway formed in a projection 96, formed integrally with the lower part of the casting.

At its lower end the stem 89 is threaded into one end of a sleeve 97 which partially 50 encloses the projection 96, and is provided at its upper end with outwardly extending pins 98 which form trunnions for a U-shaped frame composed of side rods 99 pivotally supported thereon, a cross-bar 100 connecting the lower ends of these rods.

As will be seen in Figures 4 and 5, the cross-bar 100 has a depending arm 101, which is mounted on a pin 102, supported in the link 42, this link being apertured 60 as at 103, so as to straddle the arm 101. It will be seen that as the link 42 is rocked by the action of the heart-shaped cam, the U-shaped frame composed of the cross-head 100 and the rods 99, will swing therewith 65 on trunnions 98.

It will be seen that the end of the link adjacent the aperture 103 is further apertured at 104, so that it may be suitably connected to the collar 43. It will be further seen that the lower end of the U-shaped 70 frame 45 is provided with a spring 105, anchored at its other end to a fixed pin 106 on the pump structure, this spring having a tendency to hold the frame 45 in normal position. 75

Having now described the detailed parts of the invention, I will describe the operation of these parts, although this operation will be largely obvious.

With the device mounted in position on 80 the engine bed, or in any other suitable locality, the motor is turned over either by the starter, or by hand, the closure 84 being closed so as to prevent air being drawn into the cylinders through the manifold. This 85 puts an increased suction on the gasoline line, and as the shaft 52 is revolved, gasoline will be forced from the tank, through the conduit 3, into the chamber 18. It will be understood that when the motor has once 90 been operated, this chamber will be full of gasoline under ordinary circumstances, and in that event the closure 84 need not be closed, except under unusual circumstances. With the chamber 18 filled with gasoline, as 95 the shaft 52 is revolved, the revolution of the heart-shaped cam mounted thereon, will cause a rocking of the frame 35, which will in turn be communicated to the cross-head 32, thus rocking the pinion 28. As the pinion 28 passes through a partial rotation on its axis, it will move first one, and then the other of the racks 25 in a downward direction, this downward movement forcing the 100 plungers 21 into the wells 20 and displacing 105 a quantity of fuel. The valve 11 being in the form of a check valve, will prevent the backward flow of the gasoline into the tank. Pressure, therefore, produced by the depression of the plungers, will force the valve 61 110 from its seat against its spring, thereby permitting the fuel to be forced into the conduit 72, thence upwardly through the valve 74, and into the manifold 79 to the engine.

As the gasoline passes through the valve 74, 115 the shape of the valve will have a tendency to cause it to be forced into the manifold in small particles, which will be readily vaporized.

Under normal circumstances the plunger 120 88 will be held in the position indicated in Figure 1 of the drawings, being supported there by the spring 94. The position of this plunger may be regulated by means of the nuts 91 and 92, and it will be seen that 125 dependent on the position of the plunger is the location of the cross-head 100, which connected between the ends of the link 42 determines the position of this link relative to the rod 44, thereby controlling the throw of 130

the link as the frame 45 is rocked. In other words, should the plunger 88 be lowered, this will lower the cross-head 100, and the link 42. Lowering the link 42 will vary the position of the end of the link in the U-shaped frame 45, and will place the end of the link more nearly on the axis of oscillation of the frame, thus cutting down the throw of the link, and thereby reducing the amount by which the gear 28 will be rocked. This in turn reduces the movement of the plungers 21, thus reducing the amount of fuel which is forced into the engine manifold by the movement of the plungers.

Under normal circumstances the position of the plunger 88, and the combination of the spring 94 will be so adjusted that the proper amount of gasoline will be forced into the manifold by the pumps. Should the engine, however, be called upon for a heavy load, thereby slowing its speed, this will reduce the suction of the manifold. The spring 94 will then be enabled to lift the stem 89, moving the end of the link 42 to the extremity of the rod 44, thereby giving the oscillation of the frame 45 its greatest effect in rocking the gear 28. The result of this relative movement of the parts is to increase the amount of fuel which is pumped into the manifold by means of the plungers 21. Should the load on the engine lighten, the engine will have a tendency to increase in speed, this increase increasing the amount of suction placed on the manifold. The increased suction will in turn draw the plunger 88 downwardly against the action of the spring 94. This lowering the link so as to cut down its throw, the relation of the associated parts being such as to reduce the amount of gasoline which will be pumped.

Obviously, the relation of the stem 89 and the plunger 88 with regard to the hollow casting 82, may be varied by means of the spring 94, and the adjusting nuts 91 and 92. The adjustment of the plunger 88 will depend on the normal load of the engine, and after this adjustment has been made, any variation in speed in the engine will immediately result in a variation in the amount of fuel which is being fed thereto. The effect of this regulation will be to keep the engine speed within narrow limits of variation, and once the various parts are set for the proper regulation it is not necessary that they be adjusted further, the device automatically controlling the amount of fuel which is fed to the engine, and thereby governing its speed.

It will be seen that I have provided an improved fuel feeding means for internal combustion engines well adapted to attain the purposes and objects set forth.

As many changes could be made in this construction without departing from the scope of the following claims, it is intended

that all matter contained in the above description or shown in the accompanying drawing shall be interpreted as illustrative only and not in a limiting sense.

Having thus described my invention what I claim as new and desire to secure by Letters Patent is:

1. In a device of the class described, the combination with a pair of reciprocating pumps operable in sequence, to force liquid fuel into the engine manifold of a link adapted to be reciprocated to operate said pumps, a plunger mounted in a chamber in communication with said manifold, said plunger being connected with said link and being operable by the variations in suction in said manifold to vary the throw of said link, whereby to control the action of said pumps.

2. A device of the class described, the combination of a pair of reciprocating pumps operable in sequence to force a quantity of liquid into the engine manifold, a spring-held plunger communicating with said manifold, and movable by variations in suction therein, and means operable by the movement of said plunger to vary the throw of said link.

3. In a device of the class described, the combination with a pair of pumps to force liquid fuel into the engine manifold adapted to be reciprocated to force a quantity of fuel into the engine manifold, racks mounted on the plungers of said pumps, a gear meshing with said racks, a link to rock said gear, means to reciprocate said link, and a resiliently held plunger in communication with said manifold and movable by variations in suction therein, the stem of said plunger being connected with said link and adapted to vary the throw thereof, whereby to control the amount of liquid acted upon by said pumps.

4. In a device of the class described, the combination with a pair of pumps and a manifold, to means to reciprocate said pumps including a link, means to reciprocate said link, including an oscillating frame, and means operable by the variations in suction in said manifold to vary the position of said link relative to said frame, whereby to vary the throw of said link.

5. A device of the class described, in combination, a pair of pumps, a link to reciprocate said pumps to force liquid fuel into the engine manifold, a frame on which said link is mounted, means to oscillate said frame whereby to reciprocate said link and said pumps, and a spring-held plunger communicating with said manifold, and adapted to be moved by variations in suction therein, the movements of said plunger causing variations in the position of said link in said frame, whereby to control the amount of liquid to be pumped.

6. A device of the class described, comprising in combination, a pair of pumps, racks on the plungers of said pumps, a gear meshing with said racks, a link adapted to 5 rock said gear, whereby to operate said pumps in sequence to force liquid fuel into the engine manifold, a frame supporting one end of said link, cam-operated means to oscillate said frame, whereby to reciprocate 10 said link and said pumps, and a spring-held plunger communicating with the manifold and movable by variations in suction there-

in, the movements of said plunger being adapted to vary the position of said link relative to said frame, whereby to vary the 15 amount of liquid pumped inversely with the suction in said manifold.

In testimony whereof, I affix my signature in the presence of two witnesses.

SIMON ABRAHAMS.
